US0D1067934S

(12) **United States Design Patent** (10) Patent No.: **US D1,067,934 S**
 Wang et al. (45) Date of Patent: ** Mar. 25, 2025

(54) **DISPLAY SCREEN WITH GRAPHICAL USER INTERFACE**

(71) Applicants: **ZHEJIANG ZEEKR INTELLIGENT TECHNOLOGY CO., LTD.**, Ningbo (CN); **ZHEJIANG GEELY HOLDING GROUP CO., LTD.**, Hangzhou (CN)

(72) Inventors: **Shibo Wang**, Zhejiang (CN); **Tingting Zhao**, Zhejiang (CN); **Xi Geng**, Zhejiang (CN)

(**) Term: **15 Years**

(21) Appl. No.: **35/519,606**

(22) Filed: **Oct. 30, 2023**

(80) **Hague Agreement Data**

Int. Filing Date: **Oct. 30, 2023**

Int. Reg. No.: **DM/233334**

Int. Reg. Date: **Oct. 30, 2023**

Int. Reg. Pub. Date: **Jan. 5, 2024**

(51) **LOC (15) Cl.** **14-04**

(52) **U.S. Cl.**

(57) **CLAIM**

The ornamental design for a display screen with graphical user interface, as shown and described.

DESCRIPTION

5. Display screen with graphical user interface

5.1: Front view

5.2: Front view

5.3: Front view

5.4: Front view

5.5: Front view

1 Claim, 5 Drawing Sheets
